UNITED STATES PATENT OFFICE

WILLIAM M. HOWELL, OF SEABOARD, NORTH CAROLINA.

PROJECTILE.

1,177,414.

Specification of Letters Patent. Patented Mar. 28, 1916.

Application filed May 14, 1915. Serial No. 28,138.

To all whom it may concern:

Be it known that I, WILLIAM M. HOWELL, citizen of the United States, residing at Seaboard, in the county of Northampton and State of North Carolina, have invented certain new and useful Improvements in Projectiles, of which the following is a specification.

My invention relates to projectiles for ordnance, and more especially to projectiles which are adapted to be dropped or discharged from an airship, aeroplane, or other machine designed to navigate the air.

An object of the invention is to provide a projectile with suitable means of an automatic nature whereby one or a plurality of radially disposed magazine rifles may be simultaneously fired at predetermined intervals subsequent to contact of the projectile with an object at the termination of its flight.

As a further object of the invention I contemplate a means likewise automatic in operation whereby, immediately subsequent to engagement of the projectile with a resisting object, suitable spring actuated support arms or legs will so contact or engage with said object, if horizontally flat, as to support and maintain the projectile in an upright or vertical position and consequently direct the flight of the bullets discharged through operation of the magazine rifles laterally and radially of the projectile and in a manner designed to incur the greatest destructive result.

Still further object of the invention is to provide a two-part projectile in which that portion equipped with the magazine rifles may be slowly or otherwise rotated subsequent to flight and during a firing action, to increase or widen the range of the rifles and thus attain a more deadly effect.

I further aim to provide a novel trip mechanism to be operatively associated with the parts before mentioned that the action of such parts may be timed and controlled.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying

drawings wherein like characters denote like or corresponding parts throughout the several views, and in which:—

Figure 1 is a longitudinal sectional view illustrating the position of the movable parts subsequent to contact of the projectile with the ground or other resisting object; Fig. 2 is a section on the line 2—2 of Fig. 1; Fig. 3 is a section on the line 3—3 of Fig. 1; Fig. 4 is a view similar to Fig. 1, a modified type of projectile being shown; Fig. 5 is a section on the line 5—5 of Fig. 4; Fig. 6 is a detail elevation of the control mechanism utilized as a means for directing movement of a reciprocating trigger actuating block; and Fig. 7 is a fragmentary sectional view illustrating the manner in which the support arms or legs are mounted.

Before proceeding with a description of the drawings I desire to call particular attention to the fact that while I have evolved my invention with reference to its use as a destructive agent to be dropped from machines that navigate the air, the same, if desired, may be equipped with a suitable parachute device (not shown) and shot from a mortar, cannon or other ordnance; the parachute, during descent of the projectile causing the latter to fall, point lowermost, that the rifles when extended may seek a substantially horizontal plane.

Referring now to the drawings by numerals, 1 designates a metallic substantially cylindrical pointed shell to which I secure as indicated at 2 a hollow cylindrical closure member 3. A guide rod or shaft 4 extends longitudinally of the shell 1, one end of said rod being integral with the mentioned shell and the opposite end being seated as indicated at 5 in a recess therefor of the closure member 3. A cap or trip device 6 is mounted exteriorly of the shell to inclose or cover the pointed end thereof. A rod 7 is affixed to the cap 6 and mounted to slide subsequent to contact of the cap with a movable object, longitudinally of the shaft 4 and within a concentric bore or recess 8 therein. Fingers 9 are pivotally fastened as indicated at 10 to the rod 7, which fingers, as shown to advantage in Fig. 4, project through openings 11 formed in the shaft to engage a collar 12 slidable thereon. A groove 13 is formed in the collar 12 to receive hook terminals formed upon the fingers 9 to in this manner obtain a biting

action whereby collar 12 is held in position to positively compress a spring 14 embracing the shaft and abutting at one end the metallic shell and at its opposite end the collar 12.

A second comparatively small and consequently weaker spring 15 is arranged to embrace the shaft 4 and to abut the opposite face of the collar 12 from that engaging the spring 14 and a reciprocating trigger actuating block or member 16, the latter being of a substantially conical formation whereby to engage, during reciprocation, the triggers of the magazine rifles 17 to be hereinafter described. A second collar 18 is mounted for sliding movement upon the shaft 4, this last mentioned collar providing a support means for the several rifles. Each rifle has a pivotal connection with the collar 18 as indicated at 19 in the drawings. Collar 18 carries a keeper 20 which, subsequent to sliding movement of the collar, is adapted to be engaged by a spring pressed pawl 21 fastened to the closure member 3, the pawl affording a support means whereby the collar is upheld and the several rifles positioned to discharge laterally of the projectile and to assume a position approximating a horizontal plane. The weight of the several rifles 17 and the collar 18 is sufficient to counteract the resistance offered by the spring 15, yet insufficient to counteract the tension offered by the spring 14, such arrangement, permitting, when the latter spring is released, the several rifles and the collar to be given sufficient impetus whereby keeper 20 may engage the pawl 21. When thus supported, spring 15 is of a sufficient strength to exert upward pressure on the actuating block 16 and, by reason of such pressure, cause said block to engage the several triggers whereby said triggers may be depressed and the rifles fired.

Each rifle is equipped at its outer end with a pendent closure member 22, each member, prior to a release of the collar 12, affording a closure for an opening 23 formed in the shell structure 1. As the rifles assume a horizontal position, the closure members 22 fall by gravity so as to in no way obstruct the flight of the bullets discharged from the rifles in connection with which the said closure members are used.

Coming now to a description of the mechanism utilized to reciprocate the actuating block 16, 24 designates a spring motor. A ratchet wheel 25 is adapted to be driven by the motor 24 immediately upon the release of a pivotal pawl 26. An arm 27 longitudinally slotted as at 28 has a universal connection as at 29 with the actuating member 16. A pin 30, eccentric to the axis of the ratchet 25 is mounted to operate within the slot 28 of the arm 27 and, as the pin is operable by the motor 24, it is evident that the

arm 27 will reciprocate according to the rotation of the ratchet 25 to in this manner accordingly operate the trigger actuating block or member 16.

The cap 6 before described is preferably made of a suitable malleable metal which, upon engagement of the projectile with a resisting force will cause the said cap to be depressed, the rod 7 moved longitudinally of the shaft 4 and the fingers 9 withdrawn from engagement with the collar 12. This sudden release of the spring 14 will cause block 16, collar 18 and the rifles 17 carried thereby to be thrown with force toward the closure member 3. Upon the engagement of the collar 18 with the closure member, pawl 21 will automatically lock said collar against a return movement and thus automatically position rifles 17 in a substantially horizontal plane. Closure members 22 will, as before pointed out, fall by gravity into the position shown in Fig. 1. As the block 16 is thus suddenly moved, a slight reverse movement is imparted to the ratchet wheel 25 by reason of the engagement between slotted arm 27 and pin 30. Such slight movement of the ratchet in a reverse direction will permit pawl 26 to fall by gravity out of engaging proximity with said wheel and thereafter permit motor 24 to operate unobstructed. As the member 16 is propelled by the spring 15 to a final position, it is evident that the arm 27 will move until pin 30 shall have been brought in contact with that end of the slot adjacent the free terminal of the arm. When thus positioned, rotation of the wheel 25 will cause arm 27 and consequently block 16 to be reciprocated against the tension of the spring 15 and the triggers repeatedly depressed to provide for repeated operation or firing of the magazine rifles 17.

Passing on to a description of the more complicated, yet more effectual type of projectile (the same being referred to as a modification) 24' designates a second spring motor operable to rotate that part or portion of the projectile designated 1 relatively to that part or portion designated 25, it having been pointed out hereinbefore that the projectile is made up of two parts, one part being rotatable relatively to the other. Ball-bearings 26 arranged between the relatively movable parts of the projectile facilitate rotation of the part or portion 1. A gear or pinion 27 is mounted on the motor shaft 28 to rotate the part or portion 1 when the latter shall have been released in a manner subsequently to appear. Gear teeth 29 are formed upon the closed lower end of the shell 1 to mesh with the teeth of the pinion 27. A flange 30 is formed integrally with the shell portion 25 to act with the guide rod or shaft 4 as a centering means for the shell 1.

Support arms or legs 31 are pivotally secured as at 32 within a recess 33 therefore formed in the shell part 25. The arms or legs 31 are preferably located at diametrically opposite points relatively to the axis of the shell and held, prior to contact of the cap 6 with a resisting object, in such relation to the shell part 1 as to preclude turning movement thereof and to conform approximately to the outer configuration of the projectile as a whole. Each arm or leg may therefore be said to fit a groove formed in the shell. A head portion 34 is formed upon each arm, the said head portion of each arm being provided with ratchet teeth 35 with which a pivoted pawl 36 is engageable, the mentioned pawl acting automatically to lock its associate arm in a final position subsequent to movement by gravity and the action of the spring 39 outwardly relatively to the shell and into a position intended to support the projectile in an upright or vertical manner. An eye extension 37 is formed upon the free end of the arm or leg 31 to penetrate the shell structure 1 and engage with a radial arm 38 affixed to the sliding collar 12. A spring 39 is associated with each arm or leg to exert outward pressure thereon at all times and cause said arm or leg to move outwardly or away from the projectile the moment the radial arms 38 shall have been withdrawn from engagement with the several eye extensions 37 noted above.

Operation of the last described parts is as follows: Upon distortion of the cap 6 of the shell it is evident that the collar 12 will be released. Movement of the collar in the manner before mentioned will cause the radial arm 38 to be withdrawn from engagement with the eye extensions 37 forming a part of the support legs or arms 31. Said support arms or legs being thus released, it is evident that the springs 39 will cause said arms or legs to fall or move outwardly until in engagement with the object contacting with or causing the cap 6 to be depressed, such engagement, by reason of the spread obtained, causing the projectile as an entirety to be supported and maintained in an upright or vertical position. Upon movement of the arms 31 away from the shell structure 1 it is further evident that the said structure 1 will rotate, this for the reason that the motor 24 is normally set to rotate the pinion 27 and consequently the shell structure 1. Rotation of structure 1 while the projectile is in a vertical position will cause the magazine rifles to discharge intermittently and in all directions to thus widen the range of the destructive agent.

From the foregoing, taken in connection with the accompanying drawings it is evident or apparent that the entire automatic

operation is controlled through distortion or depression of the cap member 6; that the trigger actuating block 16 will reciprocate against tension of the spring 15 the moment the clock mechanism or motor 24 shall have been released through operation of the arm 27; and that the clock mechanism or motor 24 will operate automatically immediately subsequent to outward movement of the support arms or legs 31. The support legs 31 need only be used when it is desired that the projectile be directed to fall upon a nonpenetrable object.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:

1. A projectile including a hollow shell, a rifle movable from a position entirely within to a position partially without the shell, means operable upon engagement of the projectile with an object to move said rifle, and means to discharge the rifle subsequent to movement.

2. A projectile including a hollow shell, a plurality of radially arranged rifles movable simultaneously from a position entirely within to a position partially without the shell, means operable upon the engagement of the projectile with an object to move said rifles, and means to discharge the rifles simultaneously subsequent to movement.

3. A projectile including a hollow shell, a rifle movable from a position entirely within to a position partially without the shell, means operable upon engagement of the projectile with an immovable object to move the rifle, and means to discharge the rifle subsequent to movement.

4. A projectile including a hollow shell, a trip plate located exteriorly of the shell to contact with an object at the termination of the shell's flight, a plurality of rifles movable from a position entirely within to a position partially without the shell, means operable upon actuation of the trip plate to move the rifles in the manner stated, and means operating automatically to discharge the rifles simultaneously subsequent to movement.

5. A projectile including a hollow shell, a rifle movable from a position entirely within to a position entirely without the shell,

- means operable upon engagement of the projectile with an object to thus move said rifles, and means reciprocable within the shell to repeatedly discharge the rifle subsequent to movement.
6. A projectile including a hollow shell, a magazine rifle movable from a position within to a position partially without the shell, spring means operable upon engagement of the projectile with an object to thus move said rifles, and a spring pressed trigger actuating block reciprocable within the shell subsequent to movement of the rifle in the manner stated to repeatedly discharge the rifle, substantially as described.
7. A projectile including a hollow shell, a plurality of magazine rifles movable from a position entirely within to a position partially without the shell, trip mechanism located exteriorly of the shell for contact with an object at the termination of the shell's flight spring means operable upon engagement of the trip mechanism with said object to move the rifles in the manner stated, a spring pressed reciprocatory trigger member, the mentioned member being reciprocable to repeatedly discharge the several rifles simultaneously, substantially as described.
8. A projectile including a hollow shell, a plurality of rifles movable from a position entirely within the shell to a position partially without the shell, means operable upon engagement of the projectile with an object to move said rifles, means to automatically lock the rifles when thus moved, a trigger actuating member movable to provide for a repeated simultaneous discharge of the rifles, and means to move said member.
9. A projectile including a hollow shell, a rifle movable within the shell from a position at an acute angle to the longitudinal axis of the projectile to a position at substantially right angles thereto, means operable upon engagement of the projectile with an object to move said rifle, a means to maintain the rifle against further movement when thus moved, and means operable subsequent to movement of the rifle to provide for a discharge thereof.
10. A projectile including a hollow body, a plurality of magazine rifles movable from a position entirely within to a position partially without the shell, a guide rod extending longitudinally of the shell, a support for the several rifles slidably longitudinally on said rod, means to engage said support for maintaining the rifles against further movement when partially without the shell, a trip member located exteriorly of the shell, a collar slidably longitudinally on said rod, a spring operable to slide the collar, a connection between the trip member and the collar to normally maintain said spring compressed, movement of the trip member adapted to break such connection, a reciprocatory trigger actuating block movable to simultaneously and repeatedly discharge the several rifles, and means operable subsequent to movement of the rifles in the manner stated to reciprocate said block.
11. A projectile including a hollow body having an opening formed therein, a rifle movable from a position entirely within said body to a position partially without said body, the rifle in the latter position fitting the opening aforesaid, means on the rifle to close said opening when the rifle is within the shell, and means operable upon engagement of the projectile with an object to move the rifle in the manner stated.
12. A projectile including a two-part shell, rifles movable from a position within to a position without the shell, means operable upon engagement of the projectile with an object to move said rifles, means to discharge the rifles subsequent to movement, and means to rotate one of the shell parts relatively to the other during a discharge of the rifles in the manner stated.
13. A projectile including a hollow shell, a rifle movable from an operative to an inoperative position, means operable upon engagement of the projectile with an object to move the rifle, and means to discharge the rifles subsequent to movement.
14. A projectile including a two-part shell, a rifle movable from a position within to a position without the shell, means operable upon engagement of the projectile with an object to move said rifle, means operating within the shell to discharge the rifle subsequent to movement, and means to rotate that part of the shell carrying the rifle relatively to the other part, substantially as described.
15. A projectile including a two-part shell, rifles movable from a position within to a position partially without the shell, means operable upon contact of the shell with an object to thus move the rifles, means operable within the shell to discharge the rifles simultaneously subsequent to movement, and means operating automatically subsequent to movement of the rifles to rotate one of the shell parts relatively to the other.
16. A projectile including a two-part shell, a plurality of magazine rifles movable from a position within to a position partially without the shell, means operable upon contact of the shell with an object to thus move the rifles, means operable within the shell to simultaneously and repeatedly discharge the rifles, and means to rotate one of the shell parts relatively to the other during the discharge of the rifles in the manner stated.
17. A projectile including a hollow shell,

5 a rifle movable from a position within to a position partially without the shell, means operable upon contact of the projectile with an object to thus move the rifle, and means operable by such contact to support the shell in an upright position.

10 18. A projectile including a hollow shell, a plurality of rifles movable from a position within to a position partially without the shell, means operable upon engagement of the projectile with an object to thus move said rifles, means to discharge the rifles subsequent to movement, a plurality of radial supports normally inclosed by the shell, and means operable upon contact of the shell with an object to bring said support into engagement with said object and thus support the shell in a vertical position during a discharge of the rifles in the manner 20 stated.

25 19. A projectile including a two-part shell rifles movable from a position entirely within to a position partially without the shell, means operable upon engagement of the projectile with an object to thus move said rifles, means to simultaneously discharge the rifles subsequent to movement, means operating automatically upon the engagement of the projectile with an object 30 to act as a support for the projectile and to maintain it in an upright position, and means to rotate one of the shell parts relatively to the other during a discharge of the rifles in the manner stated and subsequent to actuation of the mentioned support means, as and for the purpose set forth.

40 20. A projectile including a two-part shell, supporting arms mounted exteriorly of the shell, a means to normally maintain said arms in an inoperative position, a means operable upon engagement of the projectile with an object to release said arms, and a means to move said arms when released to an operative position.

45 21. A projectile including a two-part shell, means operating automatically upon the engagement of the shell with an object to support the shell in an upright position, means to rotate one of the shell parts relatively to the other when thus supported, rifles mounted to discharge laterally of the shell, and means to discharge the rifles.

50 22. In a projectile, a two-part shell, rifles mounted to discharge laterally of the shell,

means to discharge the rifles, means operable to rotate one of the shell parts relatively to the other during a discharge of the rifles in the manner stated, a support for the shell affixed to the stationary shell part and engaging the movable shell part to normally hold said movable part against rotation, and means operable upon the engagement of the projectile with an object to move the support from its engaging position with the rotatable shell part to a supporting position, substantially as described. 55 60 65

23. In a projectile, a two-part shell, means operable to rotate one of the shell parts relatively to the other, a support for the shell affixed to the stationary shell part and to the removable shell part to normally hold said movable part against rotation, and means operable upon the engagement of the projectile with an object to move the support from its engaging position with the rotatable shell part to a supporting position. 70 75

24. In a projectile, a support therefor, a means to normally maintain said support in an inoperative position, a means operable upon the engagement of the projectile with an object to release the support, and a means to move the support into an operative position when released. 80

25. In a projectile, a two-part shell, a means to rotate one of the shell parts relatively to the other, and a member conjunctively utilisable first as a means to preclude rotation of one of said shell parts relatively to the other, and thereafter as a support for the projectile, substantially as described. 85 90

26. In a projectile, a plurality of supports arranged radially with respect to the axis of the projectile, a means to normally maintain the several supports in an inoperative position, a means to release the said supports upon the engagement of the projectile with an object, a means to move said supports into an operative position when released, and a means to lock the said supports subsequent to movement in the manner 100 stated.

In testimony whereof I affix my signature in presence of two witnesses.

WILLIAM M. HOWELL.
